DESIGN FOR A HANDBAG

Florence E. Westmore, North Hollywood, Calif.

Application May 10, 1943, Serial No. 110,174

Term of patent 3½ years

To all whom it may concern:

Be it known that I, Florence E. Westmore, a citizen of the United States, residing in the city of North Hollywood, county of Los Angeles, and State of California, have invented a new, original, and ornamental Design for a Handbag, of which the following is a specification, reference being had to the accompanying drawing, forming a part thereof.

The figure is a perspective view of a handbag showing my new design; the shaded portions represent portions colored in contrast to the unshaded portions.

I claim:

The ornamental design for a handbag, as shown and described.

FLORENCE E. WESTMORE.
